UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 27,675, dated September 21, 1897.

Application filed August 4, 1897. Serial No. 647,133. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for Manhole-Covers, of which the following is a specification, reference being had to the accompanying drawings, forming a part thereof.

Figure 1 is a top or plan view of a manhole-cover, showing my design; and Fig. 2 is a central longitudinal section, these two views being deemed necessary to fully illustrate my design.

The leading feature of my design consists of a concave manhole-cover having one or more series of inclined spur-like ornaments grouped within the outline of the cover and surrounded by an annular series of horizontally-arranged triangular spurs projecting inward from the periphery of the cover toward the center.

Referring to the drawings, *a* is the floor, and *b* the periphery, of a concave manhole-cover. Arranged within the periphery and projecting angularly upward from the floor

of the cover are one or more series of spurs or prongs *d*, each spur being angularly inclined toward the center of the cover. Projecting inward from the periphery toward the center of the cover is an annular series of horizontally-arranged spurs or prongs *e*, which, viewed in plan or in longitudinal section, are substantially triangular. The cover, when viewed in plan, presents the appearance of a crown, whereof the annular spurs or prongs *e* are the pendants, and within which are grouped one or more series of substantially star-like ornaments, formed by the inclined spurs or spurs *d*.

Having thus described my design, what I claim as new, and desire to secure by Letters Patent, is—

A design for manhole-covers, substantially as shown and described.

In testimony whereof I have hereunto set my signature in the presence of two subscribing witnesses.

THOMAS P. GREGER.
